UNITED STATES PATENT OFFICE.

LOUIS LAUPOT, OF NEW YORK, N. Y., ASSIGNOR TO UNIVERSAL METAL CHAIN CO. INC., A CORPORATION OF NEW YORK.

FIXTURE CHAIN.

Application filed January 17, 1927. Serial No. 161,554.

My invention relates to chains, and particularly to chains adapted to utilization in an electric light fixture, to support members of the fixture and conceal the conductors supplying the lights. Lighting fixtures of the electrolier type quite commonly incorporate in the construction thereof chain members for the support of various parts. For instance, in the indirect and semi-indirect pattern of fixtures, a bowl member is used within which the lamps are positioned. These bowls are commonly supported by one or more chain members, depending from a canopy member which may be attached to the ceiling of the room, or to other convenient support. In other cases a lamp and shade with a socket are supported by a single chain from a suitable canopy, which in turn is attached to the ceiling or other support. In the past these chains have been of a very simple pattern, rather unornamental, and without suitable provision for the passage and concealment of the conductors which supply the light. Where these conductors are electric wires, they have frequently been allowed to dangle freely from the canopy to the light. In other cases they have been wound around one of the chains. In each case, therefore, the conductors have been exposed to view, and have been awkward and ungainly in appearance, and have seriously detracted from the grace and beauty of the fixture. Likewise in many other cases it has been found desirable to incorporate chain members into various structures, and to parallel the chain with a conductor, and in nearly every case the conductor has been conspicuously visible, so as to detract from the appearance of the structure.

I have invented a new and improved chain construction which is adapted to ornamentation in various ways, which makes provision for the concealment of the conductors and which is a highly desirable element for incorporation in the structure of a lighting fixture or similar ornamental device.

The chain of my invention provides a plurality of serial link members, which may desirably be made with flat portions, and a tubular portion so constructed that the tubes in successive links are in alignment, through which the conductor may be drawn, and within which it is hidden from view, the links thus being ornamental in character, sufficiently strong to support the fixture members, and

adapted to conceal a conductor. The tubular channel through the successive links may be a single channel large enough to take two conductors, for use where a single chain carries the light. Or the links may incorporate two tubes, each large enough to carry two conductors, in the event that the fixture requires two circuits, or smaller, to take a single conductor each, in the event that but a single circuit is required. Or the channel may be single and large enough for but a single conductor, for use where a plurality of chains are utilized, and entering and returning conductors may be conveyed in separate chains.

By the device of my invention I have thus produced a highly ornamental chain, of adequate strength, which is adapted to position, convey and conceal conductor members. This is the principal purpose of my invention, but other objects and details will be apparent from the following description when read in connection with the accompanying drawings, wherein:

Fig. 1 is a vertical view of a lighting fixture incorporating a length of the chain of my invention;

Fig. 2 is an enlarged view of a simple form of the chain of my invention embodied in the device illustrated in Fig. 1;

Fig. 3 is an edge view of a single half-member portion of a link of the embodiment of Fig. 2;

Fig. 4 is a view in horizontal section of a link of the embodiment shown in Fig. 2;

Fig. 5 is a side view of a modification of the chain of my invention showing two tubular portions;

Fig. 6 is a view in horizontal section of the embodiment of Fig. 5;

Fig. 7 is a side view of an alternative embodiment of my invention in which the auxiliary connecting links are formed from integral tongues of the main links;

Fig. 8 is a view in horizontal section of the embodiment of Fig. 7;

Fig. 9 is a side view of the same embodiment shown in Fig. 7 at right angles to the showing of Fig. 7;

Fig. 10 is a side view of a further modification showing a plurality of tubes at the edges thereof;

Fig. 11 is a horizontal section of the embodiment shown in Fig. 10;

Fig. 12 is a view of a further modification

showing open slots for the cooperation of the auxiliary coupling links as contrasted to the perforations of the preceding embodiments;

Fig. 13 is a view of a step in the construction showing two integral members adapted to be folded together, and

Figs. 14 to 19, inclusive, show successive steps in a preferred process for forming the links of the chain of my invention.

10 Referring to the figures, and particularly Figs. 2, 3 and 4, I provide link members as shown, which may be formed from stamped sheet metal, having flat wing portions 1 and 2, and having a semicircularly curved portion 3 as indicated in Fig. 3. Perforations 4 and 5 are provided as indicated and auxiliary link members 6 and 7 are incorporated between successive wings of the principal links for holding the series of links in proper relationship. As indicated, in Fig. 4 two of the flat members of Fig. 3 are utilized in each link, the hollows of the curved portions being positioned face to face for the formation of a tubular channel through each link. The 20 successive tubular channels in successive links are then maintained in alignment by the auxiliary links 6 and 7, forming a complete channel from end to end of the length of chain, through which suitable conductors 8 may be 30 conveyed.

A length of chain so constructed may desirably be incorporated in a fixture as indicated in Fig. 1, a canopy member 9 having a center tube 11, and a ring member 12 is provided. 35 A pair of auxiliary links 14 may be utilized to support the upper end of the chain 15 as indicated, the links 14 being inserted in the openings 4 and 5 of the links and passed through the ring member 12. A socket member 16 and shade 17 enclosing a lamp, not shown, may be attached to the lower end of the chain by means of a loop member 18 and other auxiliary link members 19 as indicated. The conductor 8 may then be passed through 40 openings in the loop members 12 and 18, and through the channel formed by the portions 3 of the successive links. By this construction, as previously stated, adequate strength for the support of the lamp and shade members is provided, and a channel for the conveyance and concealment of the conductors is formed in the supporting chain. By this means the conductor members are substantially invisible when in place, and the undesirable appearance of a loosely hanging conductor or a conductor threaded around the links of an ordinary chain is avoided.

The construction shown in Figs. 1, 2, 3 and 4 is of the utmost simplicity and is particularly adapted to utilization with a fixture having but a single chain and but a single supply circuit thereto.

In the event that two circuits are desired to the lights, a chain of the pattern shown in Figs. 5 and 6 may be utilized, in which, as in-

dicated, two channels are provided through the length of the chain. These channels may be made sufficiently large to convey two conductors in each channel, in which case two circuits are available. Or, alternatively, the 70 channels may be made smaller and less conspicuous, and may contain but a single conductor in each, thereby providing a somewhat less bulky chain, of somewhat more ornamental appearance. Likewise it is possible to provide three auxiliary coupling links as indicated, and thus obtain a greater strength, which is desirable for the support of heavier globes and lamps.

Alternatively, it is possible to avoid the utilization of the auxiliary links 6 and 7 of Fig. 2 by providing hook members integral with the main links as shown in Figs. 7, 8 and 9. In this figure flat portions 1 and 2 corresponding to the similar portions in Fig. 2 are 85 provided, with similar curved portions 3. Perforations 4 and 5 are provided as in Fig. 2, and in addition, tongue members 18 and 19 are formed upon one end of each link. These tongue members are desirably offset 90 slightly as indicated in Fig. 9 and bent at a short distance from their point of attachment to the link. The bent tongue members may then be passed through the perforations in an adjacent link, the bending continued and 95 the ends passed through openings in the first links adjacent to the point of attachment as shown. By this means a very strong connection between adjacent links is provided without the utilization of auxiliary links separate 100 from the main links.

Alternatively, it may be found convenient when a plurality of channels are desired for the passage of several conductors, to position the channels at the outer edges of the successive links, as shown in Figs. 10 and 11. This construction provides a ribbon-like chain of substantial strength, which is free from serrated edges, and free from the tendency which may occur with other patterns of chain 110 to engagement of fragments of material which may come in contact with the chain, as for instance when paper decorations are, on occasion, attached. This construction is desirably lightened and ornamented by perforations or embossing of the flat portions as indicated. The adjacent links may be held together and in alignment by auxiliary links 6 and 7 as indicated, or an integral tongue connection may be embodied similar to the 115 construction indicated in Fig. 9.

For certain uses it may be found undesirable to provide perforations of the kind indicated at 4 and 5 in Fig. 2. In such cases slots, as indicated at 21 and 22 in Fig. 12, may be provided for the positioning of the links 6 and 7. This construction is somewhat easier to assemble, and likewise provides adequate strength.

In the construction of the chain of my in-

vention, the respective halves of successive links may be formed by stamping and bending from sheet metal, similar members being combined face to face for the completion of each link. When so combined, the respective stampings of each link are held in position by the auxiliary links 6 and 7.

I prefer, however, to make each link of a single piece of sheet metal by stamping both halves from the sheet simultaneously, with the members united at a convenient point as shown in Fig. 13. This construction is preferably formed by bending the blank material to form the two semicircular channel portions, as shown in Figs. 14 and 15 thereafter bending the blank to bring the two semicircular channel portions together face to face as in Figs. 16 and 17 and then stamping out the finished link as in Figs. 18 and 19. By this means the respective halves of each link are held much more firmly in contact, and there is less tendency to spreading of the links when a conductor is drawn through the channel, which is sufficiently large to make a close fit therethrough.

I have previously described my invention as made by either one of two different processes, the simplest one resulting in a link having two separate members which are held in proper relationship by the cooperation of auxiliary links, the second embodiment describing a link made of a single piece of sheet material, folded to bring the curved portions in proper relationship to form a tube. It is, however, not necessary that the links of my invention be made in this manner.

Alternatively, it is possible to form the links of cast material as by a die-casting with the tubes as an integral element of the link, successive links being held in proper linear position in any convenient way. Alternatively, a number of modifications of the link of my invention may be made. The links may be made in halves as previously described, and the halves may be held together by suitable means, such as riveting. Or the links may be made with small projections, adapted to be folded over the adjacent member,

thereby clamping the member together. As a further modification the links may, if desired, be constructed of the previously mentioned two parts, which may then be soldered or brazed together in any convenient way for the production of a very high grade chain of unusual strength.

55

By the device of my invention I am enabled to produce an ornamental chain of substantial and adequate strength, inexpensively formed of stamped sheet metal, having a channel therethrough for the substantially complete concealment of a conductor member.

60

While I have shown several embodiments of my invention, it is capable of still other modifications therefrom without departing from the spirit thereof, and it is desired, therefore, that only such limitations shall be imposed thereon as are required by the prior art or indicated by the appended claims.

65

I claim as my invention:

70

1. An electric fixture chain consisting of a series of links, each link composed of two layers of sheet metal, said layers having opposing semi-cylindrical channels which unite to form a conduit, said layers extending laterally therefrom in close relation to one another, and having openings on either side of the conduit, and links passing through said openings in planes at right angles to the plane of the layer.

75

2. An electric fixture chain consisting of a series of links, each link composed of two layers of sheet metal, said layers having opposing semi-cylindrical channels which unite to form a conduit, said layers extending laterally therefrom in close relation to one another, and having openings on either side of the conduit, and links passing through said openings in planes at right angles to the plane of the layer, said layers being cut away between said openings and the margins of the layer to permit engagement and disengagement of said links with respect to said layers.

80

In witness whereof, I hereunto subscribe my signature.

LOUIS LAUPOT.
